Primary Examiner — Catherine Tuttle(74) *Attorney, Agent, or Firm* — QuickPatents, Inc.; Kevin Prince(57) **CLAIM**

What is claimed is the ornamental design for a set of bocce-type game balls, as shown and described.

DESCRIPTION

FIG. 1 is a perspective view of a set of bocce-type game balls, showing the new design; and, FIG. 2 is a front elevational view thereof, the rear-elevational view, left-side elevational view, right-side elevational view, top plan view, and bottom plan view all being identical thereto.

The drawings are lined and/or shaded to represent the colors blue, orange, green, yellow, and black.
